UNITED STATES PATENT OFFICE

WILFRED SEFTON AND PENNINGTON SEFTON, OF AUBURN, NEW YORK

LOUD-SPEAKER

Application filed May 18, 1927. Serial No. 192,256.

This invention relates to certain new and useful improvements in loud speakers.

The main object of the invention is the production of a loud speaker of improved characteristics in the production and amplification of sounds, especially in that the reproduction is clearer, more distinct and accurate, particularly as to sounds of comparatively low pitch, and sounds of comparatively high pitch.

A further advantage resides in the provision of two diaphragms of different sizes and formed of different materials and each adapted for more effective reproduction of sounds of particular pitches.

Other objects and advantages relate to the details of the structure and the parts thereof, all as will more fully appear from the following description, taken in connection with the accompanying drawings, in which:

Figure 1 is a front elevation of an apparatus of this invention.

Figure 2 is a sectional view on line 2—2,

Figure 1.

Figure 3 is a sectional view similar to Figure 2, but of a somewhat modified form of apparatus.

Loud speaking devices, including a cone diaphragm and a motor for actuating the same, are well-known, and in the apparatus here shown the motor is generally illustrated at —A—. The form and structure of the motor forms no portion of this invention, and any of the commonly used motors may be provided.

The apparatus as illustrated in Figures 1 and 2 comprises a hollow circular frame —1— mounted on a base —2—. One of the diaphragms, as —3—, has its outer edge clamped to the frame —1— and the diaphragm itself is of frusto-conical form, and is preferably made from some suitable paper, such as stencil paper.

The diaphragm —3— as illustrated, is of annular form, and provided with an opening at its center. This opening is closed by a second or inner diaphragm —4— as shown of conical shape and preferably formed of a material such as sheet-metal sufficiently thin to constitute a vibratory body for accurately

reproducing tones or sounds of comparatively high pitch.

The outer edge of the metallic diaphragm —4— may be secured to the inner edge of the paper diaphragm —3— in any suitable manner, as by over-lapping the edges of the diaphragms and securing them together in overlapped position by an adhesive or other suitable means. The metallic diaphragm —4— at its central portion may be formed with a hub —5— mounted upon actuating rod —6— connected in the usual manner to the motor A and suitable connection may be made between the rod —6— and the hub —5— as by means of a set screw —7—.

This construction of apparatus is found highly efficient in the accurate reproduction of sounds of varying pitch as the outer paper diaphragm —3— acts effectively to reproduce the tones of lower pitch, while the inner diaphragm —4— acts to effectively reproduce the tones of comparatively high pitch.

In Figure 3 modified form of apparatus is shown in that the two diaphragms, altho actuated simultaneously from the same motor A, are arranged separately.

The apparatus of Figure 3 comprises the same frame —1—, base —2— and motor A, but the diaphragm —8— is in this structure a substantially complete cone, and is mounted at its central portion in any suitable manner upon the rod —9— connected to motor A. The diaphragm 8 is preferably formed of suitable paper, such as stencil paper, and constitutes in itself a complete operable apparatus, but in addition thereto a second diaphragm —10— is provided which may be flat, as shown, or of other forms, secured at its central portion to the rod —11— in any suitable manner, so as to be actuated by the latter from the motor A simultaneously with the actuation of the rod —9—.

The edge of diaphragm —10— may be clamped between the rings —12— and —13—, the latter of which may be carried from the frame —1— in any suitable manner, as by brackets —14—. In this structure both diaphragm arrangements are operable structures in themselves, but are simultaneously

actuated to produce unitary sound, the diaphragm —8— acting to more effectively reproduce the lower tones, while the diaphragm —10— which is preferably formed of thin sheet metal, and is of lesser diameter, acts more effectively to reproduce the higher tones.

Altho we have shown and described specific structures as constituting perhaps preferred embodiments of our invention, it will be apparent that various and other modifications may be made in the details of the structure and the form and arrangement thereof, all within the scope of the appended claims.

15 We claim:

1. A loud speaker including a diaphragm comprising two concentric connected vibratory members formed of different material and having portions which do not overlap.

20 2. A loud speaker including a diaphragm comprising two concentric connected vibratory members formed of different material and each having a portion free to vibrate 25 without contact with the other, and means for simultaneously actuating the vibratory members.

30 3. A loud speaker comprising a cone diaphragm consisting of two concentric vibratory sections formed of different materials, one of said sections being of frusto-conical form and the other being in the shape of a cone closing the central smaller opening of the other section.

35 4. A loud speaker comprising a cone diaphragm consisting of two concentric vibratory sections of different sound reproducing characteristics, one of said sections being of frusto-conical form, and the other being 40 formed of thin metal in the shape of a cone closing the central smaller opening of the other section and secured to the adjacent edge thereof.

45 5. A loud speaker including a cone diaphragm comprising two sections, the outer one of which is frusto-conical and the inner one of which is conical, and closes the smaller open end of the other section.

50 6. A loud speaker including a cone diaphragm comprising two sections, the outer one of which is frusto-conical and the inner one of which is conical and closes the smaller open end of the other section, and is formed of thin sheet metal.

55 In witness whereof we have hereunto set our hands this 12th day of May, 1927.

PENNINGTON SEFTON.
WILFRED SEFTON.
